Primary Examiner — Garth Rademaker*Assistant Examiner* — Fitzgerald L Butac(57) **CLAIM**

We claim the ornamental design for a mobile robot, as shown and described.

DESCRIPTION

FIG. 1 is a perspective view of a mobile robot, showing our new design;

FIG. 2 is a front view thereof;

FIG. 3 is a left side view thereof;

FIG. 4 is a rear view thereof;

FIG. 5 is a right side view thereof;

FIG. 6 is a top view, on an enlarged scale thereof; and,

FIG. 7 is a bottom view, on an enlarged scale thereof.

The broken lines in FIG. 7 represent portions of the mobile robot that form no part of the claimed design. The dashed broken lines indicate the boundary between claimed and unclaimed areas.
